DESIGN FOR A HANDLE OR KNOB FOR A RHEOSTAT, OR THE LIKE

Alvin W. Krieger, Milwaukee, Wis., assignor to
Cutler-Hammer, Inc., Milwaukee, Wis., a cor-
poration of Delaware

Application August 2, 1934, Serial No. 52,785

Term of patent 14 years

To whom it may concern:

Be it known that I, ALVIN W. KRIEGER, a citizen of the United States, and a resident of Milwaukee, in the county of Milwaukee and State of Wisconsin, have invented a new, original, and ornamental Design for a Handle or Knob for a Rheostat, or the like, of which the following is a specification, reference being had to the accompanying drawing, forming part thereof.

Figure 1 is a top plan view of a rheostat knob incorporating my new design.

Fig. 2 is a side elevational view thereof.

Fig. 3 is a perspective view of the knob.

I claim:

The ornamental design for a handle or knob for a rheostat, or the like, substantially as shown.

ALVIN W. KRIEGER.
